UNITED STATES PATENT OFFICE.

HENRY B. OSGOOD, OF OSHKOSH, WISCONSIN.

TRUNK LOCK.

Application filed December 5, 1925. Serial No. 73,473.

My invention relates to trunks, and is particularly concerned with the provision of a trunk embodying novel means for locking the sections thereof together.

5 The objects of my invention are:

First, to provide a trunk comprising two sections, one of which is usually employed for housing a plurality of drawers or other receptacles and the other of which is usually employed as a wardrobe, in which suitable means are provided for hanging clothes, and locking mechanism operative from a single point for locking the two sections together at a plurality of points.

15 Second, to provide a trunk, such as described, in which the locking mechanism is located on one of the top walls of the trunk;

Third, to provide a trunk, such as described, comprising a locking-bar, that normally extends outwardly beyond the edge of the front wall of the section upon which it is mounted, and means for drawing said locking-bar to a position inside of the section;

25 Fourth, to provide a trunk, such as described, in which the locking mechanism embodies means for tightly drawing the sections together when the trunk is to be closed and for forcing the sections apart when the trunk is to be opened;

Fifth, to provide a trunk comprising locking means, such as described above, in combination with a single lock for holding the locking means in locked position;

35 And finally, to provide a trunk, such as described, that is simple in construction, economical to manufacture and easy to open and close.

Other objects and advantages of my invention will appear as this description progresses, reference being had to the accompanying drawings, in which

Figure 1 is a perspective of a trunk embodying one form of my invention;

45 Figure 2 is a detail section taken on line 2-2 of Figure 1;

Figure 3 is a view showing certain details of construction of a portion of my improved locking mechanism; and

50 Figure 4 is a vertical section taken on line 4-4 of Figure 1.

The embodiment of my invention disclosed herein comprises two sections A and B, each of which consists of front and rear walls 5 and 6, respectively, upper and lower walls 7 and 8, respectively, and a bottom

wall 9. The upper wall 7 of section B is hinged to the upper edge of the bottom wall 9 of that section by means of hinges 10 so that it can swing about a transverse axis; that is, about an axis that extends at an angle to the axis of the hinges, not shown, that connect the adjacent edges of the rear walls of the two sections.

A guide plate 11 is riveted, or otherwise secured, to the inside of the front wall 5 of section B and its lower edge is rolled over throughout its entire length, as shown at 12, and throughout a portion of its length, as shown at 13, to provide guides and retaining means for the locking-bar 14. The outer end of this locking-bar is provided with an inclined slot 15. A link 16 is pivotally connected with the inner end of the guide plate 11 by means of a rivet 17, or in any other suitable manner, and a second link 18 is pivotally connected with the inner end of the locking-bar 14 by means of a rivet 19. The other ends of the links 16 and 18 overlap each other and also overlap the lower end of the link 20 and are pivotally secured together by means of the rivet 21. The upper end of the link 20 is pivotally connected with the end wall 7 of section B in such manner that when this end wall is moved to an open position, the links 16 and 18 will form a toggle actuated by the link 20 for drawing the locking-bar 14 into the trunk, so that its outer end will not project beyond the edge of the wall to which it is secured.

When the upper wall 7 of section B is in its closed position, as shown in Figure 1, the link 20 forces the toggle links into extended position and moves the end of the locking-bar 14 out to a position where the slot therein can co-act with the stud locking-element 21 carried by the longitudinally reciprocating locking-bar 22 to lock the two sections of the trunk together. The locking bar 22 is guided in its longitudinal movement by suitable guide clips 22'.

A square, or other non-circular pivot-member 23 extends through the upper wall 7 of the section A, near the inner edge of this wall, and preferably through a plate 24 on the outside of the wall 7. A sheet metal hook locking-member 25 has a square opening formed therein for receiving the pivot-member 23 so as to insure the hook 25 turning with the pivot-member. A washer 26 is interposed between the hook locking-member 25 and the end wall of section A to

insure easy operation of the pivot-member and to prevent injury to the inner side of the end wall. A hasp, comprising the two members 27 and 28, is secured to the upper wall 7 of section A by the pivot-member 23, which passes therethrough, the opening in the part 27 of the hasp being of the same shape and size as the pivot-member 23. A head 29 on the outer end of the pivot-member prevents inward movement thereof and outward movement of the pivot-member 23 is prevented by the plate 30 having the slot 31 cut therein for receiving the neck 32 formed on the inner end of the pivot-member 23. When the plate 30 is moved to the position shown in Figure 3 and held in place by means of screws 33, or any other suitable means, outward movement of the pivot-member 23 is prevented. The part 28 of the hasp is pivoted on the part 27, as shown at 34, and its free end carries a lock 35 that is adapted to be received in a co-acting socket 36 countersunk in the outer face of the upper wall 7 of section B. A suitable key is provided for operating the lock 35 in a manner well known to those skilled in this art.

The hook locking-member 25 is provided with a slot 37 for receiving the stud 38 that is secured to the inner face of the upper wall 7 of section B, by means of the plate 39, or in any other suitable manner.

From the above description it will be apparent that by unlocking the lock 35 and lifting it upwardly, the part 28 of the hasp can be used as a handle for rotating the pivot-member 23, and that the movement of the hasp is communicated to the hook locking-member 25 in such manner that when the hasp is moved in one direction this member 40 is unlocked from the stud 38, and that when moved in the opposite direction it is locked to this stud.

One end of a link 40 is pivotally connected with the inner end of the hook locking-element 25, as shown at 41, and the other end of the link 40 is pivotally connected with one arm of the bell crank lever 42, as shown at 43. This bell crank lever is pivotally mounted upon the inner face of the top wall 7 of section A, as shown at 44, and the other end of the bell crank lever 42 is pivotally connected with the sheet metal link 45, as shown at 46. The opposite end of the link 45 is pivotally connected with one end of the bell crank lever 47 that is similar in shape to the bell crank lever 42 and pivoted to the inner face of the front wall 5 of section A, as shown at 48. This pivotal connection is shown at 49. The other end of the bell crank lever 47 is pivotally connected with the locking-bar 22, as shown at 50.

From the above description it will be apparent that when the pivot-member 23 is rotated in one direction by means of the hasp 28, the stud 21 will be forced into the slot

15 of the locking-bar 14 and drawn up to the position shown in Figure 1, thereby securely locking both sections together. Upon reverse rotation of the pivot-member 23 the stud 21 will be forced downwardly to a position that will release it from the locking-bar 14 so that the two sections can be opened. It will further be evident from a consideration of the shape of the slot 15, that when the stud 21 is moved upwardly in this slot 73 it engages the upper inclined edge of the slot and tends to pull the two sections of the trunk together. It will also be apparent that when the stud 21 is moved downwardly it will engage the opposite side of the slot 15 and tend to push the two sections of the trunk to an open position. It will also be apparent that by opening the top wall 7 of section B, the locking-bar 14 can be drawn back into the trunk where it will be out of the way. A balance strip 51, secured to section A, and dowels carry all stresses when the trunk is locked (except simple tension), and additionally tend to hold the top wall 7 of section B in locked position.

From the above description it will be apparent that I have provided a trunk construction in which two locking devices, or elements, are carried by walls extending at an angle to each other but which can be operated by a single element carried by one of said walls. It will also be apparent that by placing the lock and the means for actuating the locking mechanism on the top wall of the trunk, I have made them easily accessible and operable.

While the description and claims attached hereto refer to the front and rear, upper and lower and bottom walls of the sections of the trunk, these terms are used merely in a relative sense and are not intended to limit my construction to the particular embodiment disclosed.

While I have described the details of construction of the preferred embodiment of my invention, it is to be clearly understood that my invention is not limited to these details, but is capable of other adaptations and modifications within the scope of the appended claims.

Having thus described my invention, what I claim is:

1. A trunk comprising two sections, each having front and rear walls, upper and lower walls and a bottom wall, the adjacent edges of said rear walls being hinged together on a longitudinal axis, the upper wall of one of said sections being hinged thereon along a transverse axis adjacent the upper end of the bottom wall of said section, a pivot-member carried by the upper wall of the other section, a lock hasp secured to the outer end of said pivot-member, a hook locking-element carried by the inner end of said pivot-member, a stud locking-element

- carried by said hinged upper wall for co-acting with said hook locking-element to hold said sections together, co-acting means on said hinged upper wall and said hasp for securing the free end of said hasp to said hinged upper wall and for holding said pivot-member in one position, a locking-bar mounted to reciprocate on the front wall of the section carrying the hinged upper wall, 10 said locking-bar having an inclined slot at its outer end, means connected with said hinged upper wall for holding said locking-bar in its outermost position when said hinged upper wall is closed and for drawing said locking-bar inwardly when said hinged upper wall is open, a second locking-bar carried by the front wall of the other of said sections and mounted to reciprocate longitudinally thereof, said second locking-bar having a stud locking-element for co-acting with the walls of the slot of said first named locking-bar to pull the free edges of said front walls together when said second locking-bar is moved in one direction and to 20 push said free edges apart when said second locking-bar is moved in another direction, and connections between said pivot-member and said second locking-bar for moving said stud locking-element into unlocked position when said hasp is turned to unlock said hook locking-element, and to locked position when said hasp is turned to move said hook locking-element in locked position. 25
3. A trunk comprising two sections, each having front and rear walls, upper and lower walls and a bottom wall, the adjacent edges of said rear walls being hinged together on a longitudinal axis, the upper wall of one of said sections being hinged thereon along a transverse axis adjacent the upper end of the bottom wall of said section, a pivot-member carried by the upper wall of the other section, a lock hasp secured to said hinged upper wall and for holding said pivot-member in one position, a locking-bar mounted on the front wall of the section carrying the hinged upper wall, said locking-bar having an inclined slot at its outer end, a second locking-bar carried by the front wall of the other of said sections and mounted to reciprocate longitudinally thereof, said second locking-bar having a stud locking-element for co-acting with the walls of the slot of said first named locking-bar to pull the free edges of said front walls together when said second locking-bar is moved in one direction and to push said free edges apart when said second locking-bar is moved in another direction, and connections between said pivot-member and said second locking-bar for moving said stud locking-element into unlocked position when said hasp is turned to unlock said hook locking-element, and to locked position when said hasp is turned to move said hook locking-element in locked position. 50
4. A trunk comprising two sections, each having front and rear walls, upper and lower walls and a bottom wall, the adjacent edges of said rear walls being hinged together on a longitudinal axis, the upper wall of one of said sections being hinged thereon along a transverse axis adjacent the upper end of the bottom wall of said section, a pivot-member carried by the upper wall of the other section, a lock hasp secured to the outer end of said pivot-member, co-acting means on said hinged upper wall and said hasp for securing the free end of said hasp to said hinged upper wall and for holding said pivot-member in one position, a locking-bar mounted on the front wall of the section carrying the hinged upper wall, said locking-bar having a slot at its outer end, a second locking-bar carried by the front wall 55
5. A trunk comprising two sections, each having front and rear walls, upper and lower walls and a bottom wall, the adjacent edges of said rear walls being hinged together on a longitudinal axis, the upper wall of one of said sections being hinged thereon along a transverse axis adjacent the upper end of the bottom wall of said section, a pivot-member carried by the upper wall of the other section, a lock hasp secured to the outer end of said pivot-member, co-acting means on said hinged upper wall and said hasp for securing the free end of said hasp to said hinged upper wall and for holding said pivot-member in one position, a locking-bar mounted on the front wall of the section carrying the hinged upper wall, said locking-bar having a slot at its outer end, a second locking-bar carried by the front wall 60
6. A trunk comprising two sections, each having front and rear walls, upper and lower walls and a bottom wall, the adjacent edges of said rear walls being hinged together on a longitudinal axis, the upper wall of one of said sections being hinged thereon along a transverse axis adjacent the upper end of the bottom wall of said section, a pivot-member carried by the upper wall of the other section, a lock hasp secured to the outer end of said pivot-member, co-acting means on said hinged upper wall and said hasp for securing the free end of said hasp to said hinged upper wall and for holding said pivot-member in one position, a locking-bar mounted on the front wall of the section carrying the hinged upper wall, said locking-bar having a slot at its outer end, a second locking-bar carried by the front wall 65

of the other of said sections and mounted to reciprocate longitudinally thereof, said second locking-bar having a stud locking-element for co-acting with the walls of the slot of said first named locking-bar, and connections between said pivot-member and said second locking-bar for moving said stud locking-element into unlocked position when said hasp is turned to unlock said hook locking-element, and to locked position when said hasp is turned to move said hook locking-element in locked position.

5. A trunk comprising two sections, each having front and rear walls, upper and lower walls and a bottom wall, the adjacent edges of said rear walls being hinged together on a longitudinal axis, a pivot-member carried by the upper wall of one section, a lock hasp secured to the outer end of said 15 pivot-member, a locking-bar mounted on the front wall of the same section, said locking-bar having an inclined slot at its outer end, a second locking-bar carried by the front wall of the other of said sections, said section 20 locking-bar having a stud locking-element for co-acting with the walls of the slot of said first named locking-bar, and connections between said pivot-member and said second locking-bar for moving said stud locking-element into unlocked position when said hasp is turned in one direction, and to locked position when said hasp is turned in another direction.

6. A trunk comprising two sections, each having front and rear walls, upper and lower walls, the adjacent edges of the rear walls being hinged together on a longitudinal axis, a pair of locking, co-acting means carried by said front walls, a second pair 40 of co-acting, locking means carried by said upper walls, common means carried by one of said upper walls for actuating both pairs of locking means to locked and unlocked positions, and means for locking said common 45 means in one position.

7. A trunk comprising two sections, each having front and rear walls and an upper wall, one of said upper walls being fixed, co-acting means on the front walls of said sections for locking said sections together,

means whereby said locking means can be actuated, said last named means being mounted upon said fixed upper wall and independent of the other upper wall, and connections between said actuating means and said locking means.

8. A trunk comprising two sections, each having walls extending at right angles to each other, co-acting means on adjacent walls of said sections for locking said sections together, means on one of the walls of one of said sections extending at right angles to said first named wall whereby said locking means can be actuated, and operating connections between said actuating means and said locking means, the wall carrying said actuating means being fixed and immovable with respect to the rest of its section.

9. A trunk comprising two sections having rear walls hinged together adjacent their edges, a locking-bar mounted to move transversely of the front wall of one of said sections, the upper wall of said last named section being movably secured thereto, connections between said movable upper wall and said locking-bar for moving said bar outwardly and inwardly, respectively, when said upper wall is closed and opened, a locking-bar movably mounted on the front wall 80 of the other section and having means for co-acting with said first named bar to lock said sections together, and means whereby said locking-bar can be actuated.

10. A trunk comprising two sections, each having front and rear walls, the edges of the rear walls being hinged together, a locking-bar movably mounted on the front wall of one of said sections and projecting outwardly beyond the edge thereof when in position to lock said sections together, means on the front wall of the other section for co-acting with said locking-bar to lock said sections together, and means connected with a portion of said trunk and movable therewith for drawing said locking-bar into its section.

In witness whereof, I hereunto subscribe my name this 30th day of November, 1925.

HENRY B. OSGOOD
